UNITED STATES PATENT OFFICE.

JOHN G. FOX, OF SEATTLE, WASHINGTON.

DESIGN FOR A BOTTLE.

Application filed February 27, 1926. Serial No. 16,690. Term of patent 14 years.

To all whom it may concern:

Be it known that I, JOHN G. FOX, a citizen of the United States, residing at Seattle, Washington, in the county of King, have invented a new, original, and ornamental Design for Bottles, of which the following is a specification, reference being had to the accompanying drawing, forming a part thereof.

The figure is a side view in elevation of a bottle, showing my new design.

I claim:

The ornamental design for a bottle, as shown.

JOHN G. FOX.
